DESIGN FOR A FILING CABINET LAMP OR SIMILAR ARTICLE

Clyde D. McCann, Des Moines, Iowa

Application March 16, 1940, Serial No. 90,998

Term of patent 7 years

To all whom it may concern:

Be it known that I, Clyde D. McCann, a citizen of the United States and resident of Des Moines, Polk County, Iowa, have invented a new, original, and ornamental Design for a Filing Cabinet Lamp or Similar Article, of which the following is a specification, reference being had to the accompanying drawing, forming a part thereof.

Fig. 1 is a top plan view of my filing cabinet lamp showing my new design; and
Fig. 2 is a side elevational view thereof.

I claim:

The ornamental design for a filing cabinet lamp or similar article, substantially as shown.

CLYDE D. McCANN.
